UNITED STATES PATENT OFFICE.

* WILLIAM H. LACEY, OF WEST PALM BEACH, FLORIDA.

RAILROAD TIE.

Application filed June 1, 1926. Serial No. 112,953.

This invention relates to railroad ties, and is especially adapted for mine or industrial lines where it is often necessary to replace or shift the lines.

- 5 The principal object of the invention is to provide a tie to which the rail can be securely fastened or unfastened by wedging means and without the necessity of the use of the usual spikes.
- 10 Another object of the invention is the provision of means to form the tie in two parts to allow for ease of shipment, and means to fasten the two parts together for forming a rigid structure.

- 15 Other objects will appear as the disclosure progresses. The drawings are merely intended to indicate a possible embodiment of the invention. It is obvious that the actual needs of manufacture may necessitate certain 20 mechanical changes. It is, therefore, not intended to limit the invention to the embodiment illustrated, but rather to define such limits in the appended claim.

For a more detailed understanding of the 25 invention, attention is now called to the drawings in which a preferred embodiment is shown illustrated. In these drawings, like parts are designated by like reference characters in all the views.

- 30 Fig. 1 is a side view of the tie in an assembled position.

Fig. 2 is a top view thereof.

Fig. 3 is a section on line 3—3 of Fig. 1.

Fig. 4 is a perspective view of the wedge.

- 35 Fig. 5 is a side view of the splice plate, and Fig. 6 is an end view thereof.

Referring to the drawings in detail, numerals 1 and 2 designate both sections of the ties and 3 the splice bar fitting in grooves 40 3^a joining them together. Towards the inner ends of the ties are a pair of lugs 4 and 5 and passing through both lugs is a bolt 6 having a turnbuckle 7 in the center.

The under side of the tie is provided with

a series of dove-tailed projections 8 thus allowing the tie to be firmly imbedded in the ballast or concrete and prevent same from creeping. Above the splice bar 3 is a semi-cylindrical depression 9. This is for the purpose of allowing the necessary room for a wrench when turning the turnbuckle 7.

For fastening the rails 10 to the ties, without the use of the usual spikes, upstanding ears 11 and wedges 12 are provided. As will be seen in Fig. 1 the ears 11 and wedges 12 are provided with slots 13 to accommodate the rail flange. When the wedges are rammed in place the flanges of the rails will be firmly gripped and thus prevent the rails from creeping.

It will thus be seen that I have devised a railroad tie which is simple in construction and which can be easily shifted and can be used over and over again without any wear or replacements of parts.

Having thus described my invention, what I desire to secure by United States Letters Patent is:

In a railroad tie of the class described, a body portion formed in two sections, means 70 for fastening the said sections together, the said means consisting of a pair of lugs at the top and near the inner ends of said body portion, a bolt passing through the said lugs for drawing the sections together and a 75 splice bar inserted in grooves in said body portion, means for fastening a pair of rails to said tie, said means consisting of a pair of ears at the top of said sections having slots therein for accommodating one side of 80 the rail flanges and wedges having slots therein for accommodating the opposite side of the rail flanges, the said wedges adapted to firmly fasten the rail in place and a series of lugs underneath the said body portion for 85 firmly gripping the road ballast.

In testimony whereof I affix my signature.

WILLIAM H. LACEY.
